J. O. BURT

FUMIGATOR

Filed Oct. 12 1926

UNITED STATES PATENT OFFICE.

JOHN O. BURT, OF MEMPHIS, TENNESSEE.

FUMIGATOR.

Application filed October 12, 1926. Serial No. 141,140.

This invention relates to fumigators and it is an object of the invention to provide a device of this kind constructed in a manner whereby the discharge of the fumes may be regulated.

It is also an object of the invention to provide a device of this kind providing for the use of differing fumigating materials.

The invention consists in the details of construction and in the combination and arrangement of the several parts of my improved fumigator whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a longitudinal sectional view taken through a fumigator constructed in accordance with an embodiment of my invention with certain of the parts in elevation;

Figure 2 is a view in elevation of the device as herein disclosed;

Figure 3 is a view in top plan of the structure as herein set forth;

Figure 4 is a sectional view taken substantially on the line 4—4 of Figure 1.

As disclosed in the accompanying drawing, H denotes a supporting member adapted to be affixed at a desired location and which, as herein disclosed, comprises a cylindrical body 1 open at its top and provided at its opposite ends with the arms 2 with which suitable fastening members are adapted to co-operate.

My improved fumigator is adapted to be placed within the cylindrical body 1 of the supporting member H and comprises a lower cylindrical section 3 open at its top and which has threaded in its upper portion the lower or bottom portion of a second or upper cylindrical member 4. This member 4 is also open at its top.

The bottom wall 5 of the upper member 4 has disposed therethrough a central opening 6 continued by a depending tube 7 terminating, when the members 3 and 4 are in

assembled relation, at a point substantially central of the member 3.

The opening 6 is also continued by an upwardly tube 8 terminating substantially flush with the upper or open end of the member 4. The upper portion of the tube 8 has its wall provided with the longitudinally disposed slots 9 open at their outer ends, the flow through said slots being under control of the shank or screw 10 threaded within the upper end portion of the tube 8.

Slidably engaged within the upper member 4 is a cylindrical magazine member 11. Interposed between this member 11 and the bottom wall 5 of the member 4 is a spring 12 providing a resilient rest for the applied magazine member 11. The magazine member 11 is provided with a plurality of pockets or cavities 14 open at the top of the member 11, each of which being adapted to contain a fumigating material, material in one of said pockets or cavities preferably differing from that in the others. Rotatably mounted on the top of the member 11 is a plate 15 provided with openings 16 adapted to register with the outer or open ends of the pockets or cavities 14 whereby an effective means is provided to regulate the fumes discharged from such pockets or cavities 14.

The member 11 is provided therethrough with a central opening 17 permitting the member 11 to readily slide upon the tube 18 and the upper portion of this opening 17 is enlarged to provide a chamber 18 surrounding the upper portion of the tube 8 so that the fumes discharged from within the member 4 and as they pass out through the slots 9 may be permitted to mix with the fumes discharged from the cavities or pockets 14.

The spring 12 operates to maintain the applied member 11 spaced from the bottom 5 of the member 4 to permit a desired fumigating material to be placed within the lower portion of such member 4, the fumes of such material passing out through the opening 19 extending through the member 11. The plate 15 is also provided with an opening 20 for coaction with the upper or outer end of the opening 19.

The plate 15 may be rotated in any desired manner but, as herein disclosed, the peripheral portion thereof is provided with an outstanding knob 21.

The fumigating materials placed within the members 3 and 4 or within the various pockets or cavities 14 may be of any preferred constituency, such as insecticides, 5 rust eliminating, etc.

From the foregoing description it is thought to be obvious that a fumigator constructed in accordance with my invention is particularly well adapted for use by reason 10 of the convenience and facility with which it may be assembled and operated, and it will also be obvious that my invention is susceptible of some change and modification without departing from the principles and 15 spirit thereof and for this reason I do not wish to be understood as limiting myself to the precise arrangement and formation of the several parts herein shown in carrying out my invention in practice except as here- 20 inafter claimed.

I claim:—

1. A fumigator comprising a lower container, a hollow cylindrical member closing the upper end thereof and having therein 25 a central tube, said tube being extended through the base of said cylindrical member to enter the lower container, an upper container slidably mounted in the cylinder, spring means housed in the cylinder for 30 normally retaining the upper container in an elevated position in the cylinder, said

tube being provided at its upper end with slots, a screw threaded in the upper end of the tube and adapted to overlap the slots, said upper container having a central cavity 35 which receives the slotted portion of the tube and with its wall surfaces spaced therefrom.

2. A fumigator comprising a lower container, a hollow cylinder closing the upper 40 end of the lower container, an upper container slidably mounted in the cylinder, spring means interposed between the bottom of the cylinder and the upper container for normally holding the same in an elevated 45 position in the cylinder, said upper container having a passage-way leading from the top end thereof into the space between the upper container and the bottom of the cylinder, said cylinder having a central tube, said 50 tube extending in opposite directions and entering both containers, the upper portion of the tube being slotted, a movable member carried by the tube and adapted to overlap the slots, the upper container having a 55 socket which receives the slotted portion of the tube and with the wall surface thereof spaced from the surface of the tube.

In testimony whereof I hereunto affix my signature.

JOHN O. BURT.
